UNITED STATES PATENT OFFICE

162,849

TRUCK CARRYING TRAILER

Milford W. Lempke, Buffalo, Alfred J. Gentile, Cheektowaga, and John J. Johnson, Buffalo, N. Y., assignors to Delavan Welding Company, Inc., Buffalo, N. Y., a corporation of New York

Application July 20, 1949, Serial No. 4,005

Term of patent 14 years

(Cl. D14—3)

To all whom it may concern:

Be it known that we, Milford W. Lempke, Alfred J. Gentile, and John J. Johnson, all citizens of the United States, residing respectively at Buffalo, New York; Cheektowaga, New York; and Buffalo, New York, have invented a new, original, and ornamental Design for a Truck Carrying Trailer, of which the following is a specification, reference being had to the accompanying drawings, forming part thereof.

In the drawings:

Fig. 1 is a perspective view of the truck carrying trailer embodying the present invention.

Fig. 2 is a front elevational view of the same.

Fig. 3 is a rear elevational view thereof.

Fig. 4 is a top plan view of the same.

Fig. 5 is a side elevational view, viewed from the righthand side of Fig. 2, the opposite side being substantially the same.

We claim:

The ornamental design for a truck carrying trailer, as shown and described.

MILFORD W. LEMPKE.
ALFRED J. GENTILE.
JOHN J. JOHNSON.
